UNITED STATES PATENT OFFICE.

WILLIAM P. THOMSON, OF LANSDOWNE, AND SAMUEL G. THOMSON, OF ALTOONA, PENNSYLVANIA.

RAIL-JOINT.

SPECIFICATION forming part of Letters Patent No. 770,248, dated September 13, 1904.

Application filed December 12, 1903. Serial No. 184,896. (No model.)

To all whom it may concern:

Be it known that we, WILLIAM P. THOMSON, of Lansdowne, Delaware county, and SAMUEL G. THOMSON, of Altoona, Blair county, Pennsylvania, have invented a new and useful Rail-Joint, of which the following is a full, clear, and exact description, reference being had to the accompanying drawings, forming part of this specification, in which—

10 Figure 1 is a side elevation showing a portion of railway-track provided with our improved angle-bar. Fig. 2 is a vertical cross-section of the joint. Fig. 3 is a horizontal section of the joint. Figs. 4 and 5 are respectively a side elevation of a modified form of bar and an end view of the bars in place; and Figs. 6 and 7 are views similar to Figs. 4 and 5, showing another form of our invention.

Our invention relates to the angle-bars used 20 for suspended joints of railway-rails—that is, joints in which the meeting ends of the rails are not located over a tie; and the object of the invention is to provide a simple, strong, and efficient joint structure which will support the rail ends.

In the drawings, referring to Figs. 1 and 2, in which we show our preferred form, 22 represent the meeting ends of the rails, and 33 the ties at each side of the rail-joint. The 30 angle-bars at opposite sides of the joint are similar in character and each consists of an upper vertically-extending portion 4, the head 5 of which fits under the head of the rail, this portion merging into the intermediate sloping portion 6, which fits on the base-flange of the rail. The portion 6 is inclined outwardly and downwardly to a point beyond the edge of the rail-base and in this form merges into a flange which is bent inwardly 40 at a sharp angle in its portion 7 and has at its inner end a depending vertical portion 8. It will be noted that the portion 7 extends inwardly between the horizontal at an angle of forty-five degrees thereto. It will further 45 be noted that a vertical plane passing through the outer edge of the rail-head extends through the intermediate portion of the part 4 of the angle-bar and preferably adjacent to the center of gravity of this portion 4 and

that the center of gravity of the entire angle-bar is brought in close to the center of gravity of the rail, thus decreasing the tendency of the angle-bars to spread outwardly under the load. The depending flanges of the angle-bars are free—that is, they are not connected to each other and are free to spring under strains. The parts 4 and 6 of the angle-bar are extended longitudinally over the ties at the ends of the joint, while the depending flange portion is cut away at the ends, so that it will fit down between the ties. In using these angle-bars the angles are bolted through the rail ends in the ordinary manner, the free flanges projecting below the base of the rail. The advantages of this construction are numerous. By moving the upper portion of the angle-bar inwardly from the position shown in the Thomson patent, No. 586,804, the portion 6 is rendered of sufficient width to give plenty of room for the 65 spike-heads and for driving the same without striking the nuts or bolt-heads, thus avoiding the use of a rib such as shown in the Thomson patent, No. 586,804. This also moves the center of gravity of the angle-bar inwardly 70 toward the center of gravity of the rail. The sharp inward bending of the flange also carries this center of gravity inwardly without contacting with the bottom of the rail-base.

In Figs. 4 and 5 we show a form similar to 80 that of Figs. 1, 2, and 3, except that the flange 7^a projects vertically instead of being bent inwardly. In Figs. 6 and 7 we show a form similar to Fig. 1, except that the depending portion 8 of the flange is removed, the bar being otherwise the same as that of Figs. 1, 2, and 3. In each of these cases the flange is cut off at the ends and depends between the ties, while the ends of the bar proper project over the ties, but do not contact with them. 90

Changes may be made in the form and arrangement of the angle-bar and flange without departing from our invention.

We claim—

1. In a suspended rail-joint, an angle-bar 95 having its end portions arranged to extend over the ties, said portions being wholly above the lower face of the rail-base, and provided

with an intermediate depending flange arranged to extend between the ties and free to spring under the load, the bar having an upper head, and an intermediate vertically-extending web portion extending down from the head to the portion on the upper face of the rail-foot, this web portion being arranged so that a vertical plane at the side of the rail-head extends through said web; substantially as described.

2. In a suspended rail-joint, an angle-bar having its end portions arranged to extend over the ties, said portions being wholly above the lower face of the rail-base, and provided with an intermediate depending flange arranged to extend between the ties and free to spring under the load, the base portion of the bar being of sufficient width to provide for the spike-head without a projecting rib, the intermediate base portion of the angle-bar sloping outwardly and downwardly and fitting on the upper face of the rail-base; substantially as described.

3. In a suspended rail-joint an angle-bar having its end portions arranged to extend over the ties, said portions being wholly above the lower face of the rail-base, and provided with an intermediate depending flange arranged to extend between the ties and free to spring under the load, the bar being arranged so that a vertical plane at the side of the rail-head intersects the intermediate portion of its upper web, the intermediate base portion of the angle-bar sloping outwardly and downwardly and fitting on the upper face of the rail-base, said intermediate base portion being of sufficient width to provide for the spike-head without a projecting rib; substantially as described.

4. In a suspended rail-joint, an angle-bar having its end flange portions cut away, its remaining end portions being arranged to extend over the ties, such remaining portions being wholly above the lower face of the rail-base, the intermediate base portion of the bar sloping outwardly and downwardly and fitting on the upper face of the rail-base, said portion being of sufficient width to provide for spike-heads without a projecting rib and having an inwardly-projecting depending flange between the ties, said flange being free to

spring under the load; substantially as described.

5. In a suspended rail-joint, an angle-bar having a free depending flange extending inwardly beneath the rail-base at an angle substantially less than forty-five degrees, and free to spring under the load; substantially as described.

6. In a suspended rail-joint an angle-bar having a free depending flange extending at an inward angle beneath the rail-base and having at its inner end a depending vertically-extending portion; substantially as described.

7. In a suspended rail-joint, an angle-bar arranged to extend over the ties and having a free depending flange in its intermediate portion beneath the meeting ends of the rails, the ends of the flange being cut away to make room for the ties, said flange projecting at an inward angle substantially less than forty-five degrees, and free to spring under the load; substantially as described.

8. In a suspended rail-joint, an angle-bar having its end portions arranged to extend over the ties, and provided with an intermediate depending flange arranged between the ties and free to spring under the load, the base portion of the bar being of sufficient width to provide for the spike-head without a projecting rib, the intermediate base portion of the angle-bar sloping outwardly and downwardly and fitting on the upper face of the rail-base; substantially as described.

9. In a suspended rail-joint, an angle-bar having its end portions arranged to extend over the ties, and provided with an intermediate depending flange arranged between the ties and free to spring under the load, said flange projecting inwardly at an angle substantially less than forty-five degrees, the intermediate base portion of the angle-bar sloping outwardly and downwardly and fitting on the upper face of the rail-base; substantially as described.

In testimony whereof we have hereunto set our hands.

WILLIAM P. THOMSON.
SAMUEL G. THOMSON.
